ERNEST F. LLOYD, OF DETROIT, MICHIGAN.

METHOD OF AND APPARATUS FOR WASHING AND COOLING GAS.

1,081,455.

Specification of Letters Patent.

Patented Dec. 16, 1913.

Application filed November 3, 1911. Serial No. 658,316.

To all whom it may concern:

Be it known that I, ERNEST F. LLOYD, a citizen of the United States of America, residing at Detroit, in the county of Wayne 5 and State of Michigan, have invented certain new and useful Improvements in Methods of and Apparatus for Washing and Cooling Gas, of which the following is a specification, reference being had therein to 10 the accompanying drawings.

This invention relates to a process or method of washing and cooling gas manufactured for illuminating and heating purposes, whereby it is freed from impurities 15 by mechanical arrest or by absorption and whereby at the same time the temperature of the gas is gradually lowered to the desired point without any shock or variation that tends to throw down or remove those 20 hydro-carbons and like constituents which it is desired to retain in the gas.

In general the process or method consists in first passing a current of gas through a stream of washing liquor of lower temperature than the gas, moving in the opposite direction thereto, so that they separate at substantially the same temperatures. At the point of separation, the gas and liquor from which the impurities carried along 25 30 35 from the gas by the liquor have been trapped, are then passed through each other in the same direction and the temperature of the commingled fluids is gradually reduced from the point of reunion to the desired degree at the point of final separation. This method is carried out in an apparatus wherein the gas is caused to pass upwardly through and around successive baffles or scrubbing grids against a washing liquor 40 45 50 moving downwardly over the grids, and then downwardly through or past successive hollow baffles, or cooling grids, moving in the same direction in intimate contact with the washing liquor, the latter being preferably drawn from and returning to a receiving chamber that is common to the scrubbing and cooling sections.

In the process at hand, gas entering the apparatus at any temperature, meets falling liquor warmed to a slightly lower degree, and rising through the scrubbing baffles or grids encounters liquor somewhat cooler, keeping below but approaching the temperature of the gas all the way up 55 through the first chamber. The gas then descends through the cooling section at about

or slightly higher temperature than the cooling grids which it encounters as determined by the temperature of the water or other cooling medium in the latter, and as it passes on in company with the washing liquor, the grids are gradually made cooler so that its temperature together with that of the liquor gradually falls as it approaches the point of exit. Thus not only is the 60 65 temperature of the gas reduced without such shock as would precipitate ingredients which it is desired to retain in the gas but extraneous matter is washed out and trapped in the receiving chamber for the liquor 70 where it can be separated from the liquor by decantation or otherwise.

The invention consists in the matters hereinafter set forth and more particularly pointed out in the appended claims.

In the drawings, Figure 1 is a view, partially in elevation and partially in section, of an apparatus adapted to carry out the process or method that embodies the invention; and Fig. 2 is a view in transverse sec- 75 80 85

As herein indicated as a preferred form of construction, a suitable casing is built up of successive sections 1 each divided by an upright division wall 2 into a scrubbing chamber and cooling chamber. The division wall, which is preferably made up of a pair of separated sheets of suitable material, does not reach the top of the casing nor is provided with apertures, but its lower 90 end portions are adapted to dip into the liquor contained in the receptacle forming the bottom of the section for a water seal. A liquor inlet pipe indicated at 3, is placed conveniently to introduce liquor as desired. 95 A series of grids 5 of any preferred type is arranged in sets over each other to baffle gas entering an inlet 4 and cause it to intimately commingle with liquor drawn from the receptacle common to the scrubbing and cooling section by a suitable pump 6, and discharges through a pipe 7 and spray nozzle 8 over the top of the grids. Preferably an inclined plate 9 with upturned margins 10 deflects the liquor coming down the grids 105 to the side of the scrubbing compartment so that it runs down an apron or pipe 11 dipping into the liquor in the base, thereby preventing any splashing or agitation. Suitable deflector plates 11' may be added 110 to direct the liquor from the sides of the grids on to the plates 9.

The second or cooling compartment has a gas outlet indicated at 12 above which are series of hollow cooling baffles, pipe coils or grids 13 coupled together by suitable pipes 14 so that cooling liquid that enters the lower grid preferably passes from end to end through each grid and out of the upper grid. These pipes 14 may be within the compartment and form a part of the cooling 5 surface, the outlet connections from the grids in one chamber being such that the water or other cooling fluid employed is passed to the bottom of the next section ahead thus effecting the continuously gradual cooling 10 of the gas and elimination of impurities. 15

Gas enters the cooling compartment over the top of the division wall from the scrubbing compartment and passes down over the hollow cooled grids 13 together with 20 liquor raised from the receptacle common to the scrubbing and cooling chambers and sprayed through suitable nozzles 15 into the top of the cooling chamber. The falling liquor is again preferably diverted by an inclined board and deflecting plates 17 and quickly settles into the base, as in the scrubbing chamber. Gas which passes through the outlet 12 may, if desired, be drawn into a second inlet 18 of the scrubbing compartment of a second section and pass in a similar manner to an outlet 19 of the cooling compartment of said latter section through similar scrubbing grids 20 and down over cooling grids, encountering liquor sprayed 30 through nozzles 22 and 23 and so on through as many sections as may be desirable or the gas may pass through openings in the partition at a suitable place. Where two sections are united the common division wall separating them is preferably made of two plates 24 and 25 one of which does not reach to the bottom of the section or has in it a suitable opening for the passage of liquor and the other of which has an opening arranged 40 to form a water seal between the two sections, the liquor in the base of one of the sections falling over into the next section and thence onward, finally leaving the apparatus in the section from which the purified 45 and cold gas escapes. Or in apparatus where it is not desired to have an exterior gas connection as by the outlet 12 and inlet 18, a gasway may be made by a suitable opening through the plate 24, or both gas and liquor 50 ways may be external.

By this form of apparatus and by this process the gas while at its warmest point comes into contact with liquor at temperature slightly lower, so that it is not chilled 55 violently and so that the precipitated heavy hydro-carbons do not continue in contact with the gas at further lowering temperatures. Thereafter the gas is gradually brought to the desired temperature together 60 with the liquor with such slight disturbance

that none of the desirable constituents of the gas are thrown down. At the same time any excess of naphthalene above the temperature saturation is precipitated on the cooling grids whence it is washed down by the sprayed liquor into the liquor receptacle in the base. The liquor for effecting the washing and principal transmission of heat from the gas to the cooling water within the grids is principally derived from the precipitation of the aqueous vapors in the gas and as this liquor progresses to the succeeding sections, the gas is progressively washed with an increasing strength of the same liquor of a lowered temperature. 70

The whole apparatus is thus self contained, the processes of washing the gas, cooling the liquor, removing excess naphthalene and decanting the tars, etc., are concurrent, the temperature reduction of the gas is 85 gradual and uniform because the liquor in contact with the gas governs the gas temperature and is less rapidly affected than would be the gas alone; the transference of heat from the gas to the liquor and from the latter to the cooling water in the coils is 90 more rapid than when the foul gas is cooled direct and the scrubbing and cooling surface are continuously kept in cleaned and efficient condition by the washing of the liquor from 95 which the precipitated soots, tars, naphthalene, etc., are removed through the medium of the receiving chamber. As provision may be and usually is made for introducing extra cooling liquid into the grids, their temperatures may be accurately regulated to obtain 100 the desired result.

Obviously, changes in the details of construction may be made without departing from the spirit of the invention and I do not care to limit myself to any particular form or arrangement of parts. 105

What I claim is:—

1. A method of washing and cooling gas which consists in bringing the gas and a washing liquor of lower temperature to substantially the same temperature by passing them through a scrubber and through each other in opposite directions and in then passing them together through a cooler in the same direction and gradually lowering the temperature of the confluent fluids from the point of reunion to the desired degree at the point of final separation. 110

2. A method of washing and cooling gas which consists in bringing the gas and a washing liquor of lower temperature to substantially the same temperature by passing them through a scrubber and through each other in opposite directions and in trapping the impurities carried away by the liquor thus used, and in then passing the washed gas and decanted liquor together through a cooler in the same direction and gradually lowering the temperature of the confluent 125 130

fluids from the point of reunion to the desired degree at the point of final separation.

3. A method of washing and cooling gas which consists in bringing gas and a washing liquor of lower temperature to substantially the same temperature by passing them through a scrubber and through each other in opposite directions and baffling the intermingling fluids to trap and remove impurities therefrom, and in then passing the washed gas and decanted liquor together through a cooler in the same direction and gradually lowering the temperature of the confluent fluids from the point of union to the desired degree at the point of final separation.

4. A method of washing and cooling gas which consists in bringing the gas and a washing liquor of lower temperature to substantially the same temperature by passing them through a scrubber and through each other in opposite directions and baffling the intermingling fluids to trap and remove impurities therefrom, and in then passing the washed gas and decanted liquor together through a cooler in the same direction, and in baffling the confluent fluids by means adapted to gradually lower the temperature thereof from the point of union to the desired degree at the point of final separation.

5. Apparatus for washing and cooling gas comprising means for passing gas and a washing liquor through each other in opposite directions, a cooler, means for passing them together through the cooler while moving in the same direction, and means for gradually reducing the temperature of the confluent fluids from the point of union to the required degree at the point of final separation.

6. Apparatus for washing and cooling gas comprising means for passing oppositely moving currents of gas and washing liquor through each other, a cooler, means for passing them together through the cooler while moving in the same direction, means for removing impurities by decantation from the liquor at each period of separation from the gas, and means for gradually reducing the temperature of the confluent fluids from the point of union to the

required degree at the point of fluid separation.

7. Apparatus for washing and cooling gas comprising means for passing gas and a washing liquor through each other in opposite directions, means for decanting the used liquor, a cooler, means for passing the gas and purified liquor through the cooler while moving in the same direction, means for removing impurities by decantation from the reused liquor, and means for gradually reducing the temperature of the confluent fluids from the point of union to the desired degree at the point of final separation. 65

8. Apparatus for washing and cooling gas comprising means for causing a current of gas to flow constantly in one direction, a washing liquor receiving chamber, means for passing liquor from the chamber to the chamber through the gas in opposite direction to the flow of the latter, means for passing liquor from the chamber to a chamber through which the current of washed gas is caused to pass in the same direction as the flow of the liquor, and means for gradually reducing the temperature of the confluent fluids from the point of union to the desired degree at the point of final separation. 70

9. Apparatus for washing and cooling gas comprising means for passing gas and a washing liquor through each other in opposite directions, a receiving chamber for the liquor, means for baffling the opposed fluids and trapping impurities carried out by the liquor in the chamber, a cooler, means for passing the liquor and washed gas through the cooler in the same direction, and means for baffling the confluent fluids and trapping impurities therefrom in the chamber, constructed to gradually reduce the temperature of the confluent fluids from the point of union to the desired degree at the point of final separation. 80 85 90 95

In testimony whereof I affix my signature in presence of two witnesses.
